D. Anthony
Horse Shoe Machine

Patented Apr. 8, 1831.

6461 X

April 8, 1831

David Anthony jun^r Adams, Massachusetts
Seller's Patent.

Dated April 8th 1831.

The schedule referred to in these Seller's Patent and making part of the same containing a description in the words of the said David Anthony junior himself of his improvement being a machine for making horse shoes.

Be it known that I, David Anthony Jr. of the Town of Adams in the County of Berkshire and State of Massachusetts, have made a new and useful improvement, being a machine for making Horse Shoes, which is described as follows:

This machine consists of three principal parts: 1. The Frame. 2. The Wheel to shape and countersink the iron for the shoes. 3. The horizontal wheel, rollers, &c., to form the shoes.

Its operation is somewhat similar to the common Rolling mills for rolling iron.

1. The Frame. This is of iron about three feet long, three feet wide, and two feet four inches high.

2. The wheel to shape and countersink the iron for the shoes. Within the iron mentioned frame, and near one end of it, are placed four iron wheels about four and a half inches in diameter, and two inches in thickness, two of which run horizontally and two vertically, with their peripheries so far apart as to have a space equal to the size of the piece of iron intended for the shoe. Each wheel has an arch above it supported by two iron boxes in the frame; and the edges of each wheel are bevelled. One of the horizontal wheels has its circumference divided into three equal parts and each part shaped in the form of a segment of a larger circle than the wheel, in order to give a proper taper to the piece of iron for the shoe. The upper vertical wheel has six grooves at equal distances apart on its circumference, into each of which groove let a piece of steel or cast iron, projecting about an eighth of an inch, the piece of steel or cast iron, form the counter-sink on the under side of the shoe for the heads of the nails. There are also on the circumference of this wheel, three chisel's placed at equal distances apart to cut the bar of iron into proper lengths for the shoes as it advances between the wheels; or the wheel may be placed at unequal distances apart for different sized shoes. The wheels are geared together and made to revolve equally, by putting a wheel or bush gear on the wheel, and a pinion between the other

3. The horizontal wheel, Rollers, bars, to form the shoe.

This wheel is of iron, twenty-eight inches in diameter, one inch in thickness, turning horizontally on a axle, whose guides turn in brass boxes, in the upper and lower cross pieces of the frame; its periphery revolves near four of the four wheels above described come together, and, while the iron, when prepared for shaping into shoes, leaves them. The rim of this wheel has three spaces left in it at equal distances apart; each space being sufficiently large to admit the patterns hereafter to be described to rise and fall when necessary. From the axle or shaft of this wheel projects about an inch a small piece of iron to which is attached by a joint or hinge a lever; on the end of which lever is secured the pattern around which is formed the shoe: the lever with the pattern is held up to its place by a spring resting on an arm projecting from the axle or shaft below the lever. On the upper surface of the rim of the wheel are cases to guide the rollers hereafter to be described. To the upper part of the frame are attached two iron rollers which, with the aid of the pattern and cases form the shoe. The rollers turn horizontally and are allowed to move laterally in a mortise in the frame sufficiently large to receive them. Another roller is placed across the rim of the wheel, between, or just behind the rollers last mentioned and serves to keep the piece of iron in its place while bending. To the frame, a few inches beyond the rollers, is attached a case, which as the wheel revolves, comes in contact with the end of the lever, presses it down with the pattern, and leaves the shoe discharged, and the pattern ready to receive another. There are two other levers and patterns besides the one just described, and similar to it attached to the above mentioned axle. This horizontal wheel is geared to the four wheels first described by mitre cog wheels or bevel gearing, and is turned at the same time and by the same power that turns them.

For a further illustration of this machine reference must be had to the annexed drawings of the same forming part of this specification.

Operation. The machine being put in motion by water or steam power, and the bar of iron heated to a red heat, the end of the bar is passed into the space formed by the peripheries of the four wheels coming nearly together and tapered, comes in contact, and cuts into proper angles for the shoes by the revolution of the wheels; each piece cut after this operation and as it leaves the four wheels is received by the horizontal wheel between the rollers and pattern, but, round the latter by the revolution

of the wheel and thus formed into a shoe. It is then discharged by the slate mayon
puffing down the lever and pattern. At each revolution of the wheel three shoes
are formed, but a greater number may be made by increasing the size of the wheel.

What I claim as my invention, and which I wish to secure by Seller's Patent
is the machine for making horse shoes as above described.

In testimony that the above is a true description of my invention I have here
unto signed my name before two witnesses and made affirmation to the same
at the City of Washington this 25th day of March 1831.

Witnessed,

William P. Elliott

Thomas H. DeMille

David Anthony Jr.
